CLOTHESPIN

Fred C. McKee, 3305 31st Ave. S.,
Minneapolis, Minn. 55406

Filed June 15, 1970, Ser. No. 23,494

Term of patent 7 years

Int. Cl. D7—05

U.S. Cl. D49—1

FIG. 5

FIG. 6

FIG. 7

FIG. 8

FIG. 1 is a side elevation of a clothespin showing my new design;

FIG. 2 is an elevation taken from the opposite side thereof;

FIG. 3 is a front elevation thereof;

FIG. 4 is a rear elevation thereof;

FIG. 5 is a top plan view thereof;

FIG. 6 is a bottom plan view thereof;

FIG. 7 is a vertical section on the line 7—7 of FIG. 1; and

FIG. 8 is a horizontal section on the line 8—8 of FIG. 1.

I claim:

The ornamental design for a clothespin, substantially as shown.
